UNITED STATES PATENT OFFICE.

JOSEPH LOUIS AUTHIER, OF DETROIT, MICHIGAN, ASSIGNOR TO BURROUGHS ADDING MACHINE COMPANY, OF DETROIT, MICHIGAN, A CORPORATION OF MICHIGAN.

RECORDING MECHANISM.

1,118,998.

Specification of Letters Patent.

Patented Dec. 1, 1914.

Application filed March 17, 1913. Serial No. 754,838.

To all whom it may concern:

Be it known that I, JOSEPH L. AUTHIER, a citizen of the United States, residing at Detroit, in the county of Wayne and State of Michigan, have invented certain new and useful Improvements in Recording Mechanism, of which the following is a specification.

The present invention relates to recording mechanism in the type of machine employing independently movable type in series for denominational orders and adapted to be driven for printing purposes by the action of a hammer. This is common and well-known in various connections notably in adding and listing machines and it is with the latter class of machines that my invention is particularly concerned.

The object is to provide an improved form of means for yieldingly retracting the type. It is common to have the type spring retracted so as to rebound after having been struck and driven against the platen by the hammer, the action being a percussive one.

My invention relates more especially to machines wherein there is the so-styled "front strike" of type against a platen, this being a feature of the so-called visible writing or printing machine.

By my invention the necessity of extending the casing in which the series of type is mounted, to accommodate retracting mechanism for the type, is obviated. At the same time provision is made for a practically uniform spring retracting action upon all of the several types.

The drawings which accompany and form part of this specification illustrate a preferred form of embodiment of my invention and I have chosen for purposes of illustration to use a well-known type of adding and listing machine, to wit, that known as the "Pike".

Of such drawings Figure 1 represents in right side elevation a sufficient portion of a Pike machine to illustrate the adaptation of my invention thereto; Figs. 2 and 3 are similar vertical sections of a type-carrying lever together with an outline of a roller platen, Fig. 2 showing the parts at normal and Fig. 3 showing a type driven against the platen; and Fig. 4 is a cross-section substantially on the line 4-4 of Fig. 2.

It will be unnecessary to enter into a detailed description of the machine proper be-

cause it is so well-known both through disclosures of prior patents and through extensive commercial usage though it should be noted that the relationship of the parts is varied to some extent as compared with the disclosures of Pike Patents Nos. 763,692 issued June 28, 1904, 767,956 issued July 16, 1904, 791,941 issued June 16, 1905, and other issued patents on the Pike machine, in that the type carrying levers 403 have a contour 60 and a location relative to the roller platen 880 which, together with a corresponding variation in the mounting of the printing hammers 501 and the conformation of the inclosing casing 500, provides for exposing 65 any imprint to the view of the user of the machine at the close of the operation that does the printing, it being of course understood that in these machines it is customary to have line-spacing of paper occur in the 70 course of an operation after the printing has been done.

Passing to the matter of my present invention, each type carrying lever 403 is flanged at the type carrying portion to 75 form a housing. Thus there are front and rear flanges 4 and an end flange 4^a. The front and rear flanges are notched to receive the type 10 of which there are as usual ten with faces embossed from zero to 9. A 80 cover-plate 5 fits grooves of the flanges to close in the housing. It will be understood that the less the housing extends beyond the zero type the better so far as visibility of printing is concerned and it will be noted 85 that in the construction here shown the housing does not extend farther than necessary to provide a suitable guide for the zero type. The character of my type retracting or restoring means is such as to require no 90 appreciable upward extension of the housing to accommodate it.

The type are cut out in the side toward the body of the type carrying lever and there is arranged against the latter a shoe 100 11 of plate form curved to conform with the curvature of the front flange of the housing and normally engaging the several shoulders 10^a of the type, which shoulders mark the rear ends of the cut out portions 105 of such type. At its central portion this plate or shoe is widened and formed on the rear side with a socket 11^a. This socket receives the rounded head 12 of a lever 13 which is pivoted at 13^a to the type carrier 110

downwardly beyond the series of type. The 5 arm of the lever extending below the pivot is connected by a spring 15 to a stud at a lower point upon the type carrier and this 10 spring presses the upper longer arm of the lever forward and thus presses the plate or shoe against the shoulders of the type holding all of them forward in position to be struck by the hammer 501. The spring of course yields when the hammer strikes the 15 type. In the case of type engaged with the shoe or plate above its pivotal connection with the lever, the shoe will rock upon a fulcrum afforded by the shoulder 10^a of the 20 lowermost or 9-type as illustrated in Fig. 3, whereas in the case of type below the pivotal connection of the shoe with the lever, the fulcrum will be afforded by the shoulder of the uppermost or zero-type. In the case 25 of the two middle type, the 4 and 5 type, they engage the shoe so close to its pivotal connection with the lever that there would not be a rocking of the lever on either fulcrum above mentioned, but a bodily displacement.

It will be obvious that the shoe or plate need extend upwardly only far enough to fully engage the shoulder 10^a of the zero-type and that no extension of the housing 30 is necessary to accommodate this part of the retracting or restoring mechanism. It will furthermore be noted that the character of the mechanism is such that the spring acts with substantial uniformity upon each one 35 of these type composing the series.

It is preferable to provide means for definitely limiting the throw of the type and

to this end the lever 13 has a projection 13^b in rear of its head and designed to strike against the rear flange of the housing. 40

I claim:

1. Recording mechanism comprising a housing, a series of type pieces independently mounted to slide therein, a shoe engaging said type pieces to retract them, and a spring-actuated lever engaging the shoe and normally holding it against the several type pieces of the series, the latter when displaced singly for printing purposes displacing the shoe in opposition to the spring 50 of the said lever.

2. Recording mechanism comprising a housing, type mounted to slide therein, a shoe engaging said type to retract them, and a spring-actuated lever pivotally engaged with said shoe at its central portion. 55

3. Recording mechanism comprising a housing, a series of type independently slideable therein, a shoe engaging all the type, and a spring-actuated lever pivotally engaging the shoe centrally thereof and centrally of the series of type. 60

4. The combination of a type carrier having a housing, a series of type sliding through the housing, a hammer to act severally upon said type, a shoe engaging them to normally retract them, and a spring-actuated lever applied to said shoe centrally thereof and of the series of type. 65
